UNITED STATES PATENT OFFICE.

EDWIN M. WHEELOCK, OF WINONA, MINNESOTA.

DESIGN FOR A TRACTION-ENGINE BODY.

41,707.

Specification for Design.

Patented Aug. 22, 1911.

Application filed June 9, 1911. Serial No. 632,252. Term of patent 7 years.

To all whom it may concern:

Be it known that I, EDWIN M. WHEELOCK, a citizen of the United States, residing at Winona, in the county of Winona and State of Minnesota, have invented a new, original, and ornamental Design for a Traction-Engine Body, of which the following is a specification, reference being had to the accompanying drawing, forming part thereof.

Figure 1 is a side elevation of a traction engine body embodying and illustrating my

ornamental design. Figs. 2 and 3 are front and rear elevations, respectively, of said traction engine body.

I claim:

The ornamental design for a traction engine body, as shown.

EDWIN M. WHEELOCK.
